UNITED STATES PATENT OFFICE.

WILLIAM D. ELKINGTON, OF EAU CLAIRE, WISCONSIN.

ADJUSTABLE TIMING GEAR.

Application filed May 12, 1924. Serial No. 712,792.

To all whom it may concern:

Be it known that I, WILLIAM D. ELKINGTON, a citizen of the United States, residing at Eau Claire, in the county of Eau Claire and State of Wisconsin, have invented certain new and useful Improvements in an Adjustable Timing Gear, of which the following is a specification.

This invention relates to new and useful improvements in timing gears principally adapted for use in connection with internal combustion engines and has for its principal object to provide a means for taking up the wear caused by the meshing of the timing gear with the gear on the crank shaft.

One of the important objects of the present invention is to provide a means whereby the timing gear may be adjusted to compensate the worn gear teeth and to this end I provide a timing gear which comprises a pair of complementary sections which are adapted for circumferential adjustment with respect to each other.

A further object of the invention is to provide a means for holding the complementary sections of the adjustable timing gear in adjusted position whereby the timing gear will properly and efficiently operate.

A still further object of the invention is to provide an adjustable timing gear of the above mentioned character, which is simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a side elevation of my improved timing gear.

Figure 2 is a sectional view taken approximately on line 2—2 of Figure 1, and

Figure 3 is a similar section taken approximately on line 3—3 of Figure 1.

In the drawing wherein for the purpose of illustration is shown the preferred embodiment of my invention, the numeral 1 designates generally my adjustable timing gear and the same comprises the main section 2 which is provided with the hub portion 3, the latter being externally threaded in the manner shown at 4 and for the pur-

poses hereinafter to be more fully described. The main section 2 has the gear teeth 5 arranged in the periphery thereof in the manner well known in the art.

Threaded onto the hub portion 3 of the main section 2 is the supplemental section 6 which is adapted to abut the main section in the manner clearly shown in Figure 2 of the drawing, when in position on the hub. The supplemental section is also provided with gear teeth 7 in the periphery thereof which are adapted to cooperate with the gear teeth 5 formed in the periphery of the main section 2 and the gear teeth may be of any conventional type such as the straight or spiral forms and I do not wish to limit myself to any particular kind of gear teeth to be used for the purposes of carrying out the objects of the present invention.

Extending through the main gear section 2 are the spaced openings 8 and 9 respectively and the upper face of the main section is provided with the counter-sunk portions 10 and 11 respectively, the same being preferably arranged to cooperate with the openings 8 and 9 in the manners clearly shown in Figure 3 of the drawing. The purpose of this construction will be presently described.

The supplemental section 6 is provided with the threaded apertures 12 and 13 respectively which are arranged to cooperate with the counter sunk portions 10 and 11 provided in the main section 2 and threaded through the openings 12 and 13 are the adjusting screws 14 and 15 respectively, the inner ends of which are provided with the tapered points such as are shown at 16 and 17 respectively in the drawing. The tapered points are adapted to engage the counter sunk portions provided in the main gear section 2 and for the purpose of holding the adjusting screws in their proper adjusted positions, I provide the lock nuts 18 and 19 respectively, the same being threaded on the adjusting screws 14 and 15 and being further adapted to be seated in the counter-sunk portions 20 and 21 provided in the outer face of the supplement gear section 6 in the manner clearly illustrated in Figure 3.

The use of my adjustable timing gear may be briefly stated as follows: Normally the complementary sections are secured together so that the gear teeth on the periphery of each of the sections will be in vertical align-

ment and will mesh with the gear wheel carried by the crank shaft of the internal combustion engine. It is a well known fact that the adjustable timing gears of internal combustion engines will become worn in due time and in order to prevent the usual knocks and rattles caused thereby, the worn timing gear necessarily has to be replaced by a new one. This is an expensive proposition and also requires the loss of considerable time and labor in replacing the old and worn timing gears with a new one. To obviate the necessity of having to substitute the worn timing gear with a new one whereby considerable expense as well as time and labor are saved I provide the adjustable timing gear which may be readily and easily adjusted in the manner to be presently described.

20 Should the gear teeth on each of the complementary sections of the adjustable timing gear become worn to an appreciable extent, the sections may be circumferentially adjusted with respect to each other so as to cause the gear teeth on the periphery thereof to be brought slightly out of vertical alignment in such a manner as to take up the play or space caused by the worn gear teeth and this is accomplished by adjusting the screws 14 and 15 by first releasing one of the adjusting screws from engagement with its respective countersunk portion and by tightening the other adjusting screw and the manner of the adjustment is obvious from the construction shown. The locking nuts 18 and 19 will hold the adjusting screws in their proper adjusted positions so as to prevent the accidental displacement of the same from engagement with the countersunk portions and will further enable the complementary sections to be adjusted to their proper positions with respect to each other.

It will thus be seen from the foregoing description, that an adjustable timing gear has been provided which is simple in construction, and the parts further so arranged as to enable the complementary sections to be readily and easily adjusted whenever necessary in order to take up the play and prevent knocking or rattling. Furthermore an adjustable timing gear of the above mentioned character, will be strong and durable.

While I have shown the preferred embodiment of my invention, it is to be understood that various changes in the size, shape and arrangement of parts may be resorted to without departing from the spirit of the invention and the scope of the appended claim.

Having thus described my invention, what I claim is:—

A timing gear comprising a main section having an externally screw threaded centrally disposed hub projecting beyond one face thereof and equipped with peripheral gear teeth, a supplemental annular section placed flat against the hub carrying face of the main section, the central opening of said annular section being provided with screw threads threaded onto said hub, said main section being provided with a hole extending therethrough and said hole being countersunk at its inner end, said supplemental section being provided with a recess and a screw threaded opening extending therefrom for coaction with the opening in said main section, an adjusting screw threaded through said opening and having an inner pointed end cooperative with the aforesaid countersunk portion, and a lock nut cooperative with said screw and arranged in said recess.

In testimony whereof I affix my signature.
WILLIAM D. ELKINGTON.
